UNITED STATES PATENT OFFICE.

HARRY O. KAMMERDEINER, OF ECHO, PENNSYLVANIA.

RAIL-JOINT.

1,389,448.

Specification of Letters Patent. Patented Aug. 30, 1921.

Application filed January 18, 1921. Serial No. 438,244.

To all whom it may concern:

Be it known that I, HARRY O. KAMMERDEINER, a citizen of the United States, residing at Echo, in the county of Armstrong and State of Pennsylvania, have invented certain new and useful Improvements in Rail-Joints; and I do declare the following to be a full, clear, and exact description of the invention, such as will enable others skilled in the art to which it appertains to make and use the same.

This invention relates to an improved rail joint and one object of the invention is to provide improved means for interlocking the adjoining end portions of a pair of rails so that the rail sections will be held against longitudinal and transverse movement and further caused to move vertically together thus preventing the rails from moving out of the proper alinement and further making it unnecessary to provide fish plates or other similar means to hold the rails in close engagement with each other.

Another object of the invention is to so construct this joint that the two rail sections may be easily and quickly put together or taken apart.

Another object of the invention is to so interlock the tread portions of the adjoining rail sections that a wheel may ride easily from one rail section to another.

This invention is illustrated in the accompanying drawings, wherein:

Figure 1 is a perspective view showing rail sections connected by the improved joint.

Fig. 2 is a view showing the improved rail joint in side elevation.

Fig. 3 is a transverse sectional view taken along the line 3—3 of Fig. 2.

Fig. 4 is a top plan view of the improved rail joint.

This improved rail joint is for connecting adjoining rail sections 1 and 2. The rail end 2 has its tread cut longitudinally from one end to provide a V-shaped pocket 3 which is of less width than the tread thus providing abutment shoulders 4 for engagement by the abutment shoulders 6 provided upon opposite sides of the tapered tongue 5 which extends from the tread portion of the rail end 1. The web portions of the two rail ends are cut to provide joints 7 and 8 which fit one upon the other, thus providing a good support for the rail ends. The base portion of the rail end 2 is cut to provide a

neck 9 which tapers inwardly and downwardly and at its inner end communicates with an enlarged seat or pocket 10 which extends outwardly into the base portion of the rail upon opposite sides of the web. This seat or pocket is provided with straight cut sides and in the preferred form, the seat is rectangular as shown in Figs. 1 and 4. The base portion of the rail end 1 is cut away to provide a tapered rib 11 which conforms to the contour of the neck 9 and fits into this neck. Side arms or wings 12 extend transversely of the rail end 1 and when taken together with the portion of the base between the arms will form a block for fitting into the seat or pocket 10. It will thus be seen that when the rails are put together, the tongue 5 will fit into the pocket 3, the block formed by the side arms 12 will fit into the pocket 10 and the rib 11 will be seated in the tapered seat 9. This construction will prevent the rails from moving longitudinally out of engagement with each other and will also prevent them from having transverse movement. It will be further noted that the weight of a train passing over the rail 1 will bring the end portions into tight engagement with the end of the rail 2 and the two rail sections will be held in close contact while the train is passing from one rail to another. It is only necessary to use spikes in connecting the rails with the ties and fish plates or other connecting means between the rail ends are not necessary. When desired, the spikes can be removed and the rails easily separated.

I claim:

1. A rail joint comprising adjoining rail ends, one rail end having its tread cut to provide an inwardly extending V-shaped pocket of less width than the tread and the second rail end having its tread provided with a tapered finger fitting into said pocket, the web portions of the rail ends being cut to provide step joints, the base portion of one rail end being cut to provide an inwardly and downwardly tapering neck leading to an enlarged pocket at the base of the step joint and the second rail end having its base cut to provide a tapered rib fitting into the tapered neck and straight cut side wings fitting into the pocket.

2. A rail joint comprising adjoining rail ends having their treads interlocked against independent transverse movement and their

- web portions being cut to provide step joints, the base portion of one rail end being cut to provide an inwardly and downwardly tapering neck leading to an enlarged pocket at the base of the step joint and the second rail end having its base cut to provide a tapered rib fitting into the tapered neck, and straight cut side wings fitting into the pocket.
- 10 3. A rail joint comprising adjoining rail ends having interlocking treads and their web portions cut to provide step joints, the base portion of one rail end being cut to provide a tapered neck leading to an enlarged rectangular pocket having straight cut sides and the second rail end having its base cut to provide side wings filling said pocket and a longitudinally extending tapered rib fitting into said neck.

4. A rail joint comprising adjoining rail ends having interlocking treads and their web portions meeting in edge contact, the base portion of one rail end having a longitudinally extending downwardly tapered passage leading to an enlarged pocket and the second rail end having its base provided with side wings fitting into and filling said pocket, and a longitudinally extending downwardly tapered rib fitting into said passage. 30

In testimony whereof I have hereunto set my hand in the presence of two subscribing witnesses.

HARRY O. KAMMERDEINER.
